UNITED STATES PATENT OFFICE.

FRANK MURGATROYD, OF CLEVELAND, OHIO.

COAL AND ORE CARRIER AND TRANSMITTER.

SPECIFICATION forming part of Letters Patent No. 279,264, dated June 12, 1883.

Application filed April 13, 1883. (No model.)

To all whom it may concern:

Be it known that I, FRANK MURGATROYD, of Cleveland, in the county of Cuyahoga and State of Ohio, have invented a certain new and 5 Improved Coal and Ore Carrier and Transmitter; and I do hereby declare that the following is a full, clear, and complete description thereof.

The special purpose of this invention is for 10 loading coal into vessels by carrying the coal from the pile to the vessel and dumping it therein, or for unloading the vessel and transferring the coal to the pile, as the case may be.

Although the above-specified purpose is the 15 special object of the invention, said invention is, however, equally well adapted for unloading vessels of other freight, as ores, grain, and other commodities of a commercial nature.

The above-said invention can also be used 20 for transferring coal, ore, &c., from one particular place in the yard to another, or for loading the same into railway-cars and wagons for transportation.

Of the construction and operation of the invention above alluded to, the following is a 25 full and complete description, reference being had for illustration to the annexed drawings, making a part of this specification, in which—

Figure 1 represents a side elevation of the 30 loading apparatus; Fig. 2, a detached section; Fig. 3, a plan view of the apparatus; Fig. 4, a vertical transverse detached section taken through the line x x , and viewed in the direction of the arrow 1; Fig. 5, a view of a 35 section in the opposite direction of the arrow 1; Fig. 6, a vertical transverse section taken through the line x' x' , and viewed in the direction of the arrow 2. Fig. 7 is a transverse vertical detached section taken through the line 40 x'' x'' , and viewed in the direction of the arrow 3.

Like letters of reference refer to like parts in the several views.

As shown in the drawings, A A represent a 45 track, which may be of any desirable form and more or less in length, as circumstances may require. Said track is suspended from a suitably-constructed trestle or frame-work. (Not

shown in the drawings, as it forms no part of 50 this invention, and is not essential to a proper understanding thereof.) Said frame is mounted

upon wheels or rollers, that it may be moved from place to place, as may be necessary.

B, Fig. 1, is a carrier suspended from the track above alluded to by means of the car-wheels D D and C C, Fig. 3, on which the said 55 carriage is moved along thereon, as and for a purpose presently shown.

The carriage above referred to consists of a pair of sides, preferably of metal plates, E and F, Figs. 1 and 5, connected to each other by suitable braces and bolts, a. Said plates depend from the outside of the track, as seen in the drawings. The upper corners of the plates are re-enforced by means of the disks G, 60 through which the bolts H pass, forming the axles of the several wheels of the carrier.

Between the two plates or sides of the carrier is pivoted at b a lever, A', having three arms, I, J, and K, Fig. 1. Each of said arms 70 terminates in a conical-shaped end, forming a hook, as shown at c, d, and e, Fig. 1. Through the end e of the tri-armed lever A' is inserted a pin, f, Fig. 3, the use of which will herein-after be shown.

L, Fig. 1, is a lever consisting of two corresponding sides, as seen in Fig. 3, also in Figs. 5 and 6. The axis of said lever is at b, the ends of which are connected to each other, respectively, by the bars g h. The bar h passes 80 across the arm K of the tri-armed lever A', and over the free end of the spring M, Fig. 3.

The opposite end of the spring is made fast to said lever A' at i, as seen in the drawings.

N, Fig. 1, is a conductor or guide provided 85 with a flaring mouth. Said guide is secured between the sides of the carrier at or near the bottom, and by which the lower edges of the plates of the carrier are connected to each other and braced thereby. The upper part of 90 the conductor or guide is slotted, as seen in Figs. 5 and 6, to allow the depending arms of the levers A' and L to play backward and forward between the sides of the carrier.

In Fig. 1 one side or plate of the carrier is 95 represented as broken away, that the several levers and the conductor may be seen, also the wheel O, journaled in the corners of the carrier.

P is a sheave hung in a yoke or bail, Q, from 100 the lower end of which depends a hook, R. The upper end of the yoke is a bar, j, by which

the yoke and sheave are suspended from the hook *d* of the lever *A'*, as shown in Figs. 1 and 2.

To the carrier is attached one end of the rope *S*. Said rope passes under the sheave *P* and over the wheel *O*, and extends therefrom to a hoisting-machine. (Not shown in the drawings.)

At each end of the rail-track above described, or at any other place or places thereon that circumstances may require, are secured, respectively, the stops *T* and *U*. The stop *T* consists of the clamps *V V*, Figs. 3 and 4, fitted to the rails of the track and the frame thereof, and secured in place by the bolt *k*. In the projecting end *l* of the stop are two lugs, *m m*, Figs. 1 and 3, immediately above which is a pawl, *n*, Fig. 1. Said stop is adjustably connected to the railway, that it may be moved along thereon in either direction as the distance to run the carrier may require. The stop *U*, above alluded to, is similar to the stop *T*, and consists of the clamps *W W*, Figs. 3 and 7, secured to the railway by a bolt, *p*, that it may be adjusted thereon, according to the distance that the carrier is required to run along on the said track or way.

The operation of the above-described apparatus is as follows: Let it be supposed that the carrier *B* has been moved in the direction of the arrow shown in Fig. 1 and become attached to the stop *U* by means of the hook *c*, terminating the arm *K* of the lever *A'*, by said hook being caught on the stop-catch *a'*, as indicated by the dotted lines *b'*; and, furthermore, that the bail of the sheave *P* is detached from the hook *d* and the sheave lowered to the load to be raised, to which it is attached by the fall-hook *R*; and, also, that the rope *S* is connected to the hoisting-machine, which, as above said, is not shown in the drawings; now, as the machine winds up the rope, the sheave, with its load, is carried upward until the upper end of the bail or yoke *Q* enters the guide *M*, and is conducted thereby so far up as to impinge upon the lever *L*, which at this time is in the position indicated by the broken lines *c'*, Fig. 1. This action of the bail forces back the lower end of said lever *L* to the position shown by the full lines, which, as a consequence, depresses the upper end of the lever down upon the spring *M* and the arm *K* of the lever *A'*, causing said arm *K* to become disengaged from the stop-catch *a'*, thereby advancing the hook *d* of the lever *A'* from the position indicated by the broken line *d'* to that shown by the full line, which, as will be seen, is caught under the bar *j* of the bail or yoke *Q* of the sheave, by which it suspends the sheave and the load attached thereby from the carrier, which is now released from the stop *U*, allowing it, together with the load, to be drawn along the track or way by a continuous winding up of the rope by the hoisting-engine. When the carrier reaches the stop *T*, the hook *e* of the arm *I* of the lever *A'* impinges upon the pawl *n*, Fig. 1, which forces down the end of the lever, so that the pin *f* falls on the inner side of the stop-

catches *m m*, as indicated by the dotted lines *e'*, thereby holding the carrier from moving back or away from the stop *T*, so that the load may now be lowered to the place in which it is to be deposited, which is done by reversing the movement of the hoisting-machine, thereby unwinding the rope for that purpose. That the load may be lowered, as above said, the bail or yoke of the sheave must become detached from the hook *d* of the lever *A'*. This, however, has been already done by the depression of the arm *I* of the lever *A'*, as above described. The depression of the arm *I*, as a consequence, forces the hook *d* of the arm *J* from its engagement with the bail of the sheave, as shown, back to the position indicated by the dotted lines *d'*, so that the sheave and the load suspended therefrom are free to be lowered by the reverse action of the hoisting-machine, as above stated. The sheave having been lowered, as above described, it may be again hoisted with or without a return load, the end of the bail of which, as the sheave is drawn up by the rope, enters the guide *N* and impinges upon the lower end of the lever *L*, thereby causing the hook *d* to engage the bail, and at the same time disengaging the pins *f* from the stop catches or lugs *m m*, between which the end of the arm *I* passes, that the pins may be caught thereby for the purpose specified. The carrier, thus loaded and released from the stop *T*, is allowed to travel back down the track or way as the rope unwinds from the hoisting-machine. This return movement of the carrier is effected by gravity, the track being graded for that purpose. The carrier arriving at the stop *U*, (it may be more or less distant from the stop *T*,) the sheave is lowered for discharging the load as follows: When the carrier has reached the stop *U*, the arm *K* of the lever *A'* is forced upward by the inclined plane of the stop *U*. (Indicated by the dotted lines *C'*, Fig. 1, shown in full in Fig. 3.) This upward action of the arm *K* causes the hook *c* to engage the stop catch or lug *a'*, as indicated by the broken lines *b'*, which, as hereinbefore described, disengages the hook *d* from the bail of the sheave, so that the sheave may be lowered that its load may be discharged, which being done, the operation may be again repeated, each operation being substantially alike.

The office of the lever *L* and the spring *M* is to keep the bail of the sheave in proper position when hooked on, and to accomplish the hooking, as above stated.

What I claim as my invention, and desire to secure by Letters Patent, is—

1. In an apparatus for lifting and moving coal, ores, grain, &c., the carrier *B*, consisting of the sides *E* and *F* and wheels, whereby it is suspended from a rail track or way, and having pivoted therein a lever, *A'*, provided with three arms, each of which terminates in a hook, arranged in relation to and in combination with the catches *a'* and *m*, pawl, and inclined plane of the stops *U* and *T*, and bail of the sheave *P*, substantially as and for the purposes set forth.

2. In combination with the lever A' and bail of the sheave P, the lever L and carrier, arranged to co-operate therewith in the manner substantially as described, and for the purpose specified.

3. In combination with the levers A' and L, the spring M, substantially as and for the purpose herein specified.

4. In an apparatus for lifting and moving coal, ore, grain, &c., the combination of the levers A' and L, bail of the sheave P, and guide for conducting said bail to the levers, substantially as herein set forth.

5. In an apparatus for moving coal, ore, grain,

&c., the combination of the carrier depending from the rails or track A, levers A' and L, spring, guide, and bail Q, sheave, rope, and wheel O, catches a' and m, pawl, and inclined plane of the stops U and T, constructed and arranged to operate and co-operate in the manner substantially as set forth, and for the purposes specified.

In testimony whereof I affix my signature in presence of two witnesses.

FRANK MURGATROYD.
